CECIL L. TURNER, OF NEW YORK, N. Y., ASSIGNOR OF ONE-HALF TO SIDNEY H. HART,
OF HOUSTON, TEXAS.

STILL.

1,091,781.

Specification of Letters Patent. Patented Mar. 31, 1914.

Application filed April 10, 1912. Serial No. 689,700.

To all whom it may concern:

Be it known that I, CECIL L. TURNER, a subject of the King of Great Britain, and a resident of the city of New York, Tompkinsville, borough of Richmond, in the county of Richmond and State of New York, have invented a new and Improved Still, of which the following is a full, clear, and exact description.

10 Among the principal objects which the present invention has in view are: To provide a still wherein fractional and continuous distillation may be performed; to provide a still adapted for the production of 15 fractional distillation of the hydro-carbon oils or other volatile liquids; to provide means for conserving the heat employed in the distillation; and to provide means for increasing the output of stills adapted for 20 practical distillation.

Reference is to be had to the accompanying drawings forming a part of this specification, in which similar characters of reference indicate corresponding parts in all 25 views, and in which—Figure 1 is a front view of a still constructed and arranged in accordance with the present invention; Fig. 2 is a back view of the same; Fig. 3 is a vertical section taken on the line 3—3 in 30 Fig. 4; Fig. 4 is a top plan view of the end section of the still; Fig. 5 is a detail view, on enlarged scale, showing a support and drain gutter for the evaporating tables employed in the present invention; and Fig. 6 is a cross section taken on the line 6—6 in 35 Fig. 5.

As shown in the accompanying drawings, the still is employed in the distillation or refining of hydro-carbon and crude oil. In 40 the operation of the invention, the oil is deposited in a tank 11 which is disposed at any suitable height. The oil is thence delivered to a basin 13, being the first of a series of similar basins. Thence the oil 45 flows through a dividing wall, by means of an overflow pipe 16, to a second basin 14, and thence through a dividing wall, by means of an overflow pipe 17, to a third basin 15. It will be understood that this 50 series may be extended. In each of said

basins, the oil is subjected to the action of a pre-heating system, later described. From the last basin of the series, in the present instance the basin 15, the oil is conducted by an overflow pipe 18 to a pump 19, 55 to be thence delivered by way of a pipe 20 to a heat-transfer tank 21. From the tank 21, by way of a delivery pipe 22, the oil is deposited in a trough 23, which is the initial member of a series of troughs, each connected by a spreading or draining table. The second trough of the series referred to is designated by the numeral 24, which, as best seen in Figs. 1 and 4 of drawings, is disposed at the opposite side of the first 60 evaporating chamber.

The troughs 23 and 24 are disconnected, except as the oil is passed from the one to the other by an overflow and across an evaporating table, as later set forth. The trough 24 and the trough 25, the latter being the third of the series of troughs referred to, are connected by a pipe loop 29. The troughs 26 and 27, the fourth and fifth of said series, are similarly connected; the 75 troughs 25 and 26; 27 and 28 being disconnected, though mounted within the same chamber, except as the oil flows from one to the other over an evaporating table. From the trough 28, the final of the series, 80 the oil is conducted by a pipe 30 (Fig. 2) to the cylinder section 31 of the transfer tank 21.

The cylinder section 31 is drained by a pipe 32, which leads the heavier or body portion of the oil off to a reservoir or de- 85 canting station.

Disposed between each pair of troughs, such as 23 and 24 and 25 and 26, is a table 33. The tables 33 are supported by the troughs 23, 24, 25, 26, 27 and 28, and are 90 each provided with a steam box 34, whereby the table 33 is heated. Each of the boxes 34 is supplied by a steam-heating system, said boxes being connected by means of nipples 36, Fig. 4, to a supply pipe 35, and each box 95 being provided with a steam-delivery pipe 37, Fig. 3. The pipe 37 is returned to the boiler or steam generator to maintain the circulation of the heat system.

By means of suitable valves 38 Fig. 4 dis- 100

posed on the steam-supply pipe 35, the degree of heat produced in each of the boxes 34 is predetermined and maintained. It will be observed that the flow of the heated steam through the boxes 34 is transverse to the flow of the oil from between the troughs 23 and 24, and between the troughs 25 and 26 and the troughs 27 and 28; or, in other words, the flow of the heating medium is perpendicular to the progression of the oil under treatment. This insures that the oil is, during the passage through each evaporating chamber, subjected constantly to one degree of heat; therefore, the gravity of the distillate may be accurately predetermined by regulating the heat in each of the boxes 34 by manipulating the valves 38 to increase or diminish the flow of steam in the said boxes.

20 Each evaporating chamber is separated from the other by domes 39, 40 and 41, which rest upon the flanges 42 of the troughs contained within said chambers. Each dome is suitably constructed to provide a sufficient area to promote the evaporation of the lighter gases from the body of the oil or liquid passing over the table 33 mounted in each chamber. The vapors, as evolved, rise to the upper portion of the domes, and 30 are there drawn off through pipes 43 and bonnets 44, (Fig. 3) one of which each dome is provided with. The bonnets 44 are preferably elongated horizontally, to remove the vapors evolved in the chambers at a certain 35 level.

The various pipes 43 are each extended through the walls of the basins 13, 14 and 15, and are operatively connected with a crosshead drum 45, into which the vapors are delivered, and from which they are extracted by cooling coils 46. The coils 46 are disposed substantially as shown in the drawings, and are at the lower end connected with a drum 47. The drums 47 are each provided 40 with delivery pipes 48. Each pipe 48 is directly connected with separate tanks 49, into which the condensed liquid or oil is delivered by pipes 50. It will be understood that there is a tank 49 assigned individually 45 to each of the domes 39, 40 and 41, and that the product drawn from each of the said domes under usual conditions varies, the variation being controlled in the manner above stated; to wit, by maintaining in the boxes 34 a constant heat, and in maintaining 50 a constant flow of the oil in said dome over the table 33 therein.

To accommodate the operation of the still, whereby the various products may be mixed, 60 I connect the various pipes 50 by means of cross pipes 51 Fig. 4. Under normal conditions, the pipes 51 are closed by valves 52 connected therewith. Under normal conditions, the pipes 50 are open to the tanks 49,

but when desired, these pipes may be closed 65 by valves 53, thereby diverting the flow of oil from any particular one of the tanks for delivery to another of the battery of tanks.

To assist the circulation of the vapors evolved in the said evaporating chambers, a 70 fan 58 Fig. 3 is employed. The fan is driven from any suitable power supply, being connected therewith by a pulley 59. From the fan 58, air is delivered by way of a pipe 60, to a horizontally extended pipe 75 61. The pipe 61 is connected by branch pipes 62 to nozzles 63 Fig. 3. The nozzles 63 are each introduced into the pipes 43 by which the heated vapors are drawn from the various domes 39, 40 and 41. When the fan 80 58 is in operation, the pressure in the pipes 60, 61 and 62 drives the vapors downward through the pipes 43, to produce therein an action resembling the action of a pulsometer or injector of usual construction and operation. The current established in this manner in the pipe 43 operates to rapidly and positively draw off the vapors from the various domes 39, 40 and 41, and to therein 85 create a slight rarefaction which promotes 90 the evolution of the desired vapors from the oil or liquid in each dome.

Certain oils have mixed therewith water, which, under favorable conditions will precipitate out of the oil. Such conditions are 95 to be found in the troughs 23 to 28 inclusive, where the inclined bottoms 54 deliver the water precipitated from the oil to sumps 55 Fig. 5. From the sumps 55, the water is drawn by drainage pipes 56, for delivery to 100 any convenient waste or pound. Under the ordinary service conditions of the still, a water level is maintained in the drainage system, which level rises to above the entrance of the drainage pipe 56 within the 105 sumps 55.

It will be understood from the foregoing description showing the method employed for heating the oil preliminary to introducing the same into the evaporating chambers, 110 that certain light but valuable volatiles will be given off by the oil in the basins 13, 14 and 15, which volatiles, rising under the box 34, would be expanded, and when accumulated, might form a pressure injurious to 115 the perfect operation of the still. It is to provide an escapement for these volatiles from the basins 13, 14 and 15, that I provide draw-pipes 57 Fig. 3. Each pipe is connected with the bonnets 44 or pipes 43, to 120 be influenced by the circulation in the said pipes 43, to form a slight but sufficient draft in said basins before the oils heat therein. When thus equipped, it will be seen that the light volatiles referred to are captured, and 125 condensed in the coils 46, and carried, with the vapors, from the domes 33, 34 and 35.

A pipe is provided to draw off the oil or

liquid from the basins 13, 14 and 15, when such action is deemed necessary or desirable. For this purpose, it will be noted that the floors of the various basins are dipped to 5 the center, to deliver to drain pipes 65, which pipes are in open communication with the pipe 64.

From the foregoing, it will be seen that the crude oil delivered from the tank 11 is 10 circulated through the basins 13, 14 and 15, being there subjected to the heat of the coils 46, until, when the oil is delivered by 15 the pipe 18 to the pump 19, it is raised in temperature considerably above the temperature of the body of oil contained in the tank 11. As this partially-heated oil is 20 pumped through the transfer tank 21, it is again heated by the heavy oil passing through the jacket 31, for delivery by the 25 pipe 32 to a reservoir or decanting station, as above stated. When, now, after passing through the tank 21, the oil is delivered to the first of the domes 39, it has already been heated to a degree requiring but little further heat to evolve the vapors of the lighter 30 oils. From this point on, the oil is successively increased in heat, evolving thereby from the body oil the various grades of lighter oils, which grades are predeterminedly arranged as to the fractional distillation desired. From the last of the domes, the highly heated body oil is delivered to the tank 21, to, in its turn, pre-heat, by transfer to, the oil being introduced into the domes 39, 40 and 41, in the 35 manner above outlined.

It will also be observed that the heat of the domes and of the vapors liberated therein is conserved by passing the said vapors 40 through the coils 46 to transfer the heat of the oil passing through the basins 13, 14 and 15. The conservation of heat thus outlined is in practice found such as to require a minimum supply of steam to the boxes 34.

45 In the perfect running of the still, it will be understood that all of the initial heat for the still is supplied by the steam-heating system, of which the boxes 34 comprise a part.

50 Having thus described my invention, I claim as new and desire to secure by Letters Patent:—

1. A still, having a crude-oil supply embodying a plurality of evaporating chambers, each chamber having a spreading floor disposed between troughs for receiving and delivering the oil in each chamber, said chambers being connected in series, means for returning the oil from the delivery trough of the last of the series of chambers to the source of supply; a steam-heating system for said chambers, embodying a series of radiators disposed adjacent the floor of each of said chambers, said radiators being

arranged in series; and means for regulating the temperature of said radiators. 65

2. A still, having a crude-oil supply embodying a plurality of evaporating chambers, each chamber having a spreading floor disposed between troughs for receiving and delivering the oil in each chamber, said chambers being connected in series, means for returning the oil from the delivery trough of the last of the series of chambers to the source of supply; a steam-heating system 70 for said chambers, embodying a series of radiators adjacent the floor of each of said chambers, said radiators being arranged in series; means for regulating the temperature of said radiators; means for conveying 75 away from said chambers the vapors generated therein; and means for condensing said vapors by passing the same through the crude-oil prior to the introduction thereof to the first of said chambers. 80

3. In a still such as described, the combination of a crude-oil supply embodying a tank, a basin in open communication with said tank, a heater, a series of evaporating chambers, means in each of said chambers 90 for spreading the oil in a thin layer while passing therethrough, and an apparatus for maintaining the circulation of said oil in the order named; a steam-heating system embodying a plurality of radiators, disposed 95 each under and adjacent the floor of said compartments, a heater for the oil preliminary to the introduction thereof to the initial evaporating chamber, means for regulating independently the heating medium supplied to said radiators, and means 100 for supplying steam to said radiators and said heater, to cause the steam to travel in a direction the opposite of that followed by the oil; and a plurality of condensing coils, 105 each being situated in said basin, each of said coils being in open communication with one of said evaporating chambers, said coils being adapted to transfer the heat of the vapors drawn from said chambers to the oil 110 supply in said basin.

4. In a still such as described, the combination of a crude-oil supply embodying a tank, a basin in open communication with said tank, a heater, a series of evaporating 115 chambers, means in each of said chambers for spreading the oil in a thin layer while passing therethrough, and an apparatus for maintaining the circulation of said oil in the order named; a steam-heating system 120 embodying a plurality of radiators, disposed each under and adjacent the floor of said compartments, a heater for the oil preliminary to the introduction thereof to the initial evaporating chamber, means for regulating independently the heating medium supplied to said radiators, and means 125 for supplying steam to said radiators and

said heater, to cause the steam to travel in a direction the opposite of that followed by the oil; a plurality of condensing coils, each being situated in said basin, each of said 5 coils being in open communication with one of said evaporating chambers, said coils being adapted to transfer the heat of the vapors drawn from said chambers to the oil supply in said basin; and means in open 10 communication with said coils for accelerat-

ing the passage of the vapors from said chambers to said coils.

In testimony whereof I have signed my name to this specification in the presence of two subscribing witnesses.

CECIL L. TURNER.
